METHOD OF FORMING TAIL-TIE

William F. Rea, Toledo, Ohio, assignor, by mesne assignments, to L. O. F. Glass Fibers Company, Toledo, Ohio, a corporation of Ohio

Application December 30, 1954, Serial No. 478,622

1 Claim. (Cl. 242—18)

My present invention relates to fiber packaging and more particularly to the providing of yarn in a continuous fashion for furnishing the same to a twister, a builder, or a knitting machine, for example. Still more specifically this invention relates to a novel pирн band.

In the supplying of fiber to a twisting operation a magazine creel is utilized to temporarily store the fiber to be used in the twisting operation. In magazine creeling, as described hereinafter, a tail end of a first fiber package or pирн is suitably tied to a forward end of a second pирн or fiber package in such manner that the fiber of both packages may be withdrawn from the package in a continuous fashion. Accordingly any number of packages may thus be supplied to a twister in a continuous production operation.

A primary object of the present invention is to provide for use in conjunction with a pирн a novel pирн band, or more specifically a fiber receiving band. The pирн band is applied to the pирн prior to fiber packaging as noted more fully hereinafter, and the function of this pирн band is to provide the necessary tail for securing a first fiber package to a second package.

A principal object of the invention is to describe a novel method of attaining a tail on a pирн or package of fiber.

The invention will be more fully understood by reference to the following detailed description and accompanying drawings wherein:

Figure 1 illustrates a preferred embodiment of the pирн band of invention;

Figure 2 illustrates a pирн or fiber package in combination with a pирн band as the fiber is initially being wound upon the band and pирн;

Figure 3 illustrates a completed package with the pирн band thereon;

Figure 4 illustrates a fiber package with the pирн ring removed and the tail end free for securing to the forward end of another package;

Figure 5 is a front elevational view of the pирн band of Figure 1;

Figure 6 is a rear elevational view of the pирн band of Figure 1;

Figure 7 is a view of a further embodiment of the pирн band of invention;

Figure 8 is a view of yet another embodiment of the invention; and

Figure 9 schematically illustrates the general mode of operation of magazine creeling utilizing the tails provided in the method of invention.

Referring to the drawings, and first particularly to Figures 1, 5 and 6, a preferred embodiment of the pирн band or belt is indicated generally by the numeral 1. This band may suitably be of natural or synthetic rubber or of a plastic material such as polyethylene and preferably has a degree of resiliency such that it may be fitted relatively tightly over a pирн end.

The band has a large central opening 2 and comprises a circumferential channel 3 closed on the bottom by a thin base 5. Upwardly extending from the base 5 bound-

2

ing the channel on either side thereof are circumferential rims 7, 9. The rim 7 is suitably of solid material therearound.

The rim 9 is preferably slotted through as indicated at 11 for communication of channel 3 with an outer side of the belt. One slot 11 is sufficient but for the sake of dynamic balance I prefer to employ at least two oppositely disposed slots and most suitably for use in conjunction with glass fibers the slots are in quadrature. 10 The band is shown in Figure 2 in combination with a pирн 13, the bottom of the base 3 being fitted snugly over the pирн and with the rim 9 on the side remote from the extremity 15 of the pирн.

Shown partially on the pирн band and pирн in Figure 2 at 17 is a glass strand which is to be wound on the pирн to form a package such as is shown in Figure 3. The strand 17, it will be noted, has an extreme loose starting end 18 and the strand is wound around the base 5 a plurality of times, the windings preferably crossing over each other somewhat; then an inner portion of the strand is passed through a slot 11 and reversely drawn around the pирн as indicated. This initial operation of setting up the pирн band and pирн is preferably performed by hand, the extreme end 18 being held as by a thumb 20 on the rim 7 while the strand is started onto the band and pирн. Thus the pирн band or belt will contain the strands laterally as well as circumferentially.

With the pирн set as in Figure 2 the pирн and pирн band are rotated in the direction indicated by the arrow 30 on a suitable winding machine; this rotation is usually carried out at high speed, for example 6400 r.p.m. During this winding the rotation is such that the yarn does not unwind from the band and the extremity 18 is held down by both the strands of yarn in the channel and 35 the windage effect occasioned by the rotation.

At high speeds the band 1 is affected by centrifugal force and tends to pull out from the pирн thus setting up very considerable stresses in the band. These stresses tend to rupture the pирн band at the slots 11 and I have found that it is desirable, particularly when the band is of a soft material to employ four of the slots 11; this has the effect of distributing the stresses more uniformly and rupture is inhibited. When employing a plurality of slots they should be positioned symmetrically around the band to provide dynamic balance therein.

I prefer to employ a rubber or neoprene material of a durometer of about 90 as such is sufficiently rigid to resist stresses under the action of the centrifugal forces usually encountered at winding speeds—and further such material does not abrade the glass fibers passing through the slot 11. However, other materials are suitable and the selection thereof is dependent to some extent upon, for example, the speeds encountered and the nature of the material being wound.

With the glass fibers of this specific example completely filling the pирн (Figure 3) and the rotation thereof stopped the fibers or strands on the band are cut through as indicated at 19 and the portion 21 which remains provides the desired tail (Figure 4).

The utilization of the combination of pирн and pирн band prevents any loosening of the strands of fibers as winding takes place. Further the pирн may be shipped by the manufacturer to a processor with the pирн band thereon, the tail being securely retained in position all the while. Cutting at 19 to secure the tail 21 is then carried out by the fiber processor.

The tail 21 of a first pирн 23 is indicated in Figure 9 as being secured to a forward end of a second pирн 25. 70 The pирнs 23, 25 are mounted on a support 27 which is provided with upstanding spindles 29, 31. Pирн 23 as shown is mounted on spindle 29, pирн 25 being on spindle 31.

Also as shown in Figure 9 a guide eye 33 is provided above the support 27; the strand of glass fibers may then as shown be passed continuously through the guide eye to, for example, a twister as indicated by the legend. It is to be noted that when the glass fibers on pирн 23 have been run out the tail 21 provides that pирн 25 will be automatically run out thereafter.

Further since pирн or package 25 has a tail 35, provided as described, this tail may be run to the forward end of a new filled package mounted on the spindle 29.

The pирн band thus provides a secure retaining means for a fiber package tail during the winding of the package. For glass fibers which abrade easily the material of the band is most suitably rigid enough to resist the centrifugal force and soft enough to inhibit abrasion. Further since the fibers at 19 will in production operations be cut through quickly by a sharp knife it is desirable that the material used should not cut easily. A neoprene or rubber compound which is relatively stiff, that is of about 90 durometer, meets these requisites very satisfactorily.

The preferred embodiment of the band as shown in Figures 1, 5 and 6 has four slots for communication of the band channel with the outer side of the band. These slots may as illustrated have walls which taper slightly and as already noted the slots are uniformly spaced.

However, as shown in Figures 7 and 8 the bands for the winding of glass fibers may also have two or three slots; with only one slot at high speeds the stress distribution around the band is uneven and accordingly the life of the band is adversely affected. Three slot bands however perform nearly as well as four slot bands.

The utilization of bands having unslotted rims is possible where the material being packaged does not abrade readily, the strand in this instance passing across the rim 9 onto the pирн. I have found however that in general with glass fibers the strands abrade unduly and the tail is lost if the strand is not passed through a slot such as that shown at 11 in the figures.

The life of the pирн bands is substantially indefinite even with glass fibers when the band is appropriately

balanced for high speed as indicated hereinbefore. The band itself is most suitably an integral body of somewhat resilient material such as rubber or neoprene and is readily and cheaply molded.

It will be understood that this invention is susceptible to modification in order to adapt it to different usages and conditions and accordingly, it is desired to comprehend such modifications within this invention as may fall within the scope of the appended claim.

10 I claim:

A process of winding a package from a continuous strand of fibrous material which comprises, initially winding a strand as a plurality of circumferential turns about a removable element of a mechanical support, drawing the inner end of the strand from the circumferential turns in a reverse direction while retaining the circumferential turns of the strand in position and while supporting the reversely drawn portion, continuing the passage of the strand from the reversely drawn portion about the support to lock the said inner end on the support, then winding a main body of the strands on said support, cutting the circumferential turns other than the reversely drawn end to remove the same from the removable support and thus leave the inner end as a tail, and then removing said support to provide a package with an access tail.
